DESIGN FOR A CAN OPENER

Harry C. Wilson, Sherman Oaks, Calif., assignor
to Robert H. Clark, Los Angeles, Calif.

Application November 2, 1946, Serial No. 134,484

Term of patent 7 years

(Cl. D22—2)

To all whom it may concern:

Be it known that I, Harry C. Wilson, a citizen of the United States, residing in the city of Sherman Oaks, county of Los Angeles, and State of California, have invented a new, original, and ornamental Design for a Can Opener, of which the following is a specification, reference being had to the accompanying drawings, forming a part thereof.

Fig. 1 is a perspective view of the can opener showing my new design, showing the can opener viewed to illustrate the top thereof; Fig. 2 is a side elevation of the can opener; and Fig. 3 is a bottom elevation of the can opener.

I claim:

The ornamental design for a can opener, as shown.

HARRY C. WILSON.
